(57) **CLAIM**

The ornamental design for a biochemistry analyzer, as shown and described.

DESCRIPTION

1.1 is a front view of the biochemistry analyzer;

1.2 is a back view thereof;

1.3 is a left view thereof;

1.4 is a right view thereof;

1.5 is a top view thereof;

1.6 is a bottom view thereof; and

1.7 is a perspective view thereof.

The broken lines are used to illustrate unclaimed environment and disclaim portions of the biochemistry analyzer, and form no part of the claimed design.
